UNITED STATES PATENT OFFICE.

GEORGE H. CHAPPELL, OF NEW YORK, N. Y.

BICYCLE.

SPECIFICATION forming part of Letters Patent No. 441,627, dated November 25, 1890.

Application filed August 15, 1890. Serial No. 362,136. (No model.)

To all whom it may concern.

Be it known that I, GEORGE H. CHAPPELL, a citizen of the United States, and a resident of New York, in the county of New York and State of New York, have invented certain new and useful Improvements in Bicycles, of which the following is a specification.

Figure 1 is a side view of a bicycle equipped with my improvements; Fig. 2, a top view of the same; Fig. 3, a cross vertical section, enlarged, of the wheel-hub and shaft, showing the manner of applying the mechanism for increasing speed; Fig. 4, a rear view of the motor and its connecting mechanism; Fig. 5, a side view of the same; Fig. 6, a top view of the motor-shaft, showing the connection with the shaft which transmits motion to the wheel-axle; Fig. 7, a vertical section of axle on crank-shaft through line X of Fig. 3, looking outward; and Fig. 8, a top view of the same.

The object of my invention is to construct a bicycle or other vehicle with mechanism whereby the operator can propel the same either by foot mechanism or by a motor, or by a combination of foot and motor, and in the employment of these means the following features are provided for, namely: first, a method whereby the speed of the drive-wheel can be increased or decreased without changing the speed of the crank or motor shaft; second, providing means whereby the crank-shaft can be entirely disengaged from the wheel; third, mechanism for throwing the motor-shaft into engagement with the crank-shaft, whereby the motor can be employed as an aid in propulsion or the foot-power reinforce the motor; fourth, a reversing-lever for entirely cutting out the motor and reversing the motor-shaft, so that the momentum of the vehicle or its motion on a downgrade can be employed to wind up the spring-motor, where a motor of that character is used; fifth, means for winding up the motor by the momentum of the wheel or its motion on a downgrade by which the speed of the winding mechanism is increased, thereby utilizing the power and at the same time utilizing the winding process for the purpose of braking the vehicle.

One of the advantages of the invention consists in so constructing these various devices that they can be operated while the vehicle is in motion, only three levers being employed

for the different maneuvers, and these are so located and arranged that no extraordinary skill will be required to manipulate them.

Referring to the drawings, A represents the main or drive wheel, mounted on a shaft B and journaled in the frame C, and D the guide-wheel secured to the pivotal standard E, the upper end of which is provided with handles E'. The main horizontal bar C of the frame, through the central disks C' C' of which the shaft B is journaled, has a rearwardly and upwardly projecting arm F, which meets the curved rib or backbone F', which arcs over the wheel A. To the backbone is attached the seat G on the standard G'.

Power is transmitted to the crank-shaft B through the medium of foot-levers H H, the forward ends of which are provided with stirrups, while their rear ends are hinged to the lower ends of the links H' H', which swing from the rearwardly-projecting ribs F. The cranks I of the shaft are therefore attached to the levers H H approximately midway between the ends, and the stirrups of these levers are thus brought directly below the region of the seat G. Power is also transmitted to the crank-shaft by means of a motor through the shaft J, the rear end of which has a small miter-gear J', while the crank-shaft has a similar gear J². The forward end of the shaft J is journaled in the hanger K and has a miter-wheel K' on its projecting end.

L is the motor case or box, secured to the frame C in any suitable manner, and in cases where spring-motors are used I employ a lever L' and ratchet-wheel L², with a coacting pawl for winding up the spring or springs in the case. The shaft of the motor has a gear M, which transmits motion through an intermediate gear-wheel to a wide-faced pinion M on one end of the horizontal shaft M². This latter shaft is journaled through the frame C, and has on its other end two miter-gears N N', which face each other, and both of which are fixed to the shaft M². These gears N N' are designed to mesh with the gear K' on the shaft J. The gears N N' are so located on the shaft, however, that only one of them can be in engagement with the gear K' at a time, and by moving the shaft M² endwise both of the gears can be disengaged or either one

brought into action at will. This is accomplished by means of the lever O, which is hinged to the motor-case L, while its lower end is bifurcated and placed over the grooved 5 collar O' of the gear N. The face of the motor-case has a rack-bar P, with notches therein, for the purpose of holding the lever O in the three positions required. It will be seen that the wide face of the gear M' permits the 10 shaft M² to move endwise a limited distance without breaking connection with the gear in the motor-case. The shaft M² is further provided with a fixed pinion Q, and the frame C has a projecting pin Q', which is so located 15 that the pinion comes in contact therewith only when the gears N N' are disengaged from the gear K'. The object of this gear and pin is to prevent the motor from setting or keeping the shaft M² in motion while the 20 motor is cut out or during the interval that is necessary to reverse the shaft.

As shown in Fig. 4, the gear N' is represented in engagement with the gear K'. In this position the motor is transmitting power 25 to the crank-shaft B through the shaft J, the upper end of the lever O being in the meantime turned to the right. When the lever O is moved to the central notch on the rack-bar P, the gears K' N' are disengaged and the 30 motor set free. To prevent racing, the gear Q and pin Q' are engaged, thereby holding the shaft M² from turning. In this position the vehicle can be impelled by foot-power in the usual way. Should it be desired to wind 35 up the motor by the motion of the vehicle, the lever O is thrown to the left, so as to bring the gears N K' in contact. By this means the shaft M² is reversed and the spring in the motor wound up.

40 The wheel of this invention is peculiar in its construction, being so arranged as to permit the operator to increase or decrease the speed of the wheel independently of the crank-shaft and without stopping the motion 45 of the shaft.

In a former application filed by me July 23, 1890, the serial number of which is 359,628, I set forth an invention for increasing or decreasing speed on a single shaft. I utilize 50 that invention in this wheel, and therefore it is not necessary to set forth the peculiar construction of the mechanism herein except so far as it may be necessary to show the adaptation of that invention to a bicycle-wheel.

55 As shown in Fig. 3, the crank-shaft has thereon the three miter-gears a b c, of which the first only is fixed to the shaft, as shown by the pin d. The pinion c is connected with the end of the tubular hub or collar e, to 60 which the wire spokes f of the wheel are attached in the ordinary manner. The other end of the shaft has a collar or sleeve g, provided with a flange on its inner end, and a right-angled arm i projecting therefrom and 65 extending along parallel with the shaft B. The inner end of this arm i has a pin j projecting toward the shaft B, and on this pin

is placed a miter-gear k, which meshes with both the gears a b. Between the gears b c is an arm l, attached to the shaft and held in 70 position by means of the set-screw m. The outer end of this arm has a miter-gear n, which meshes with the gears b c. By this train of gearing motion is increased from the shaft B to the hub e, and the vehicle thus 75 propelled with greater velocity. The tubular hub e has its end on the left side journaled loosely on the collar g, and its outer end is flanged, as shown at h, and has teeth 80 q, and corresponding thereto and by the side thereof the collar g has projecting teeth p. As shown more clearly in Fig. 7, it will be seen that the inner face of the disk C' is provided with a housing r, in which is placed a bolt s, the lower end of which engages with 85 the teeth p of the collar g, while the opposite end of the bolt has a rod or bar t, which extends up to a suitable lever in reach of the operator on the seat. The bolt s has a curved arm u, which extends around the collar to the 90 opposite side of the shaft B, where it is equipped with a broad-faced pinion v, which meshes with the teeth q p in both the collar g and the hub-flange. The bolt s and the pinion v are so arranged relatively to each 95 other that when the bolt is in engagement with the teeth p the pinion v is clear of the teeth q p, and, if desired, the bolt s and the pinion v may both be clear of the teeth q p. When, however, the pinion v is in contact with the 100 teeth q p, the bolt is clear of the teeth p.

It will be seen that when the bolt s engages with the teeth p the collar g is prevented from turning around with the shaft B. The speed of the tubular hub e is therefore accelerated 105 through the medium of the intermediate gearing. The moment, however, that the bolt s is withdrawn the hub e is free to turn on the shaft B, and the cranks I can remain at rest while the vehicle is moving forward. 110 When, now, the small pinion v is brought in contact with the teeth q p, both the hub e and the collar g turn together at the same speed as the shaft B, thereby enabling the rider to exert a greater force, but a slower speed; or he 115 may augment the speed by again throwing in the bolt s.

It is obvious that when the hub e travels at, say, three times the speed of the shaft B power transmitted back from the hub e to the 120 crank-shaft B, as in going downgrade, will enable me to wind up the spring in the motor with ease without detracting much from the momentum of the vehicle. If, however, I wish to exert a braking force while winding 125 up the mechanism on a downgrade, the bolt s can be withdrawn and the pinion brought into engagement with teeth q p, and the motor can be wound up at the same rate of speed as is given by the shaft B, instead of at the 130 reduced rate of speed obtained by the bolt-connection.

What I claim as new is—

1. A bicycle having on the crank-shaft the

entire train of multiplying or reducing gearing, in combination with a bolt for disconnecting the gearing and a gear for connecting the shaft and the hub of the wheel, substantially as herein shown.

2. A bicycle having on the crank-shaft the entire train of multiplying or reducing gearing, in combination with a motor having an interposed reversible shaft for throwing the 10 motor in the train and impelling the bicycle or winding up the motor by the momentum of the drive-wheel, substantially as herein set forth.

3. A bicycle having on the crank-shaft the entire train of multiplying or reducing gearing, in combination with a bolt secured to the 15 shaft-boxing for disconnecting the train of gearing from the shaft, and with the motor and motor-shaft having an intervening reversing 20 and cut-out shaft and gearing, substantially as shown.

4. A bicycle having on the crank-shaft the entire train of multiplying or reducing gearing, in combination with a gearing for connecting and disconnecting the crank-shaft 25 and the drive-wheel, and with a motor and motor-shaft having an intervening reversing and cut-out shaft and gearing, substantially as herein set forth.

5. A bicycle having a tubular hub, one end 30 of said hub being journaled loosely on the crank-shaft and the other end on a loose collar on the same shaft, said collar being connected with a train of multiplying gearing 35 which transmits increased motion to the hub at its opposite end, in combination with mechanism for attaching and detaching the crank-shaft, substantially as herein set forth.

6. A bicycle having a tubular hub one end 40 of which is loosely journaled on the crank-shaft and the other end on the collar on the same shaft, said collar projecting beyond the hub and provided with a toothed gearing in line with the toothed gearing on the end of 45 the hub, in combination with a small pinion with a wide face movable to and from the two sets of gears, whereby both hub and collar are caused to rotate in unison or independently of each other, substantially as herein 50 set forth.

7. A bicycle having a tubular hub one end of which is loosely journaled on the crank-shaft and the other end on a collar on the same shaft, said collar projecting beyond the 55 hub and provided with a toothed gearing in line with the toothed gearing on the end of the hub, in combination with a sliding arm on the shaft and boxing having on one side of the shaft a bolt to engage with the teeth of 60 the collar and on the opposite side of the

shaft a wide-faced pinion for engaging with the teeth of both the collar and hub, substantially as herein set forth.

8. A motor for vehicles, having attached thereto a shaft geared directly to the motor 65 and provided with a limited longitudinal movement, one end of said shaft having two fixed miter-gears facing each other and adapted to mesh alternately with the miter-gear of the drive-shaft, said motor-shaft having thereon a small pinion which engages with a lug or pin on the frame during the interval between the engagement and disengagement of the miter-gears when the motor-shaft moves back and forth, substantially as herein set 70 forth.

9. The combination of the longitudinally-movable motor-shaft having two fixed miter-gears facing each other, the drive-shaft miter-gear between the same and engaging therewith, the toothed gear on the shaft, and fixed 80 pin or lug on the frame for engaging the gear, and lever having a toothed rack-bar for moving the motor-shaft longitudinally, substantially as herein set forth.

10. In a bicycle, the drive-wheel having a tubular hub and within said hub on the drive-shaft the entire set of gearing for increasing the speed of the wheel, which consists of a collar on the shaft having an arm carrying 90 a loose miter-gear, and on the shaft next to the collar a fixed miter-gear, and on the shaft facing the fixed gear a loose gear, both engaging with the loose gear on the arm, and the loose miter-gear on an arm on the shaft 95 engaging with loose miter-gears on opposite sides, one of the gears being connected with the loose gear in the first set of miters and the other gear being connected with the hub of the drive-wheel, substantially as herein set 100 forth.

11. A loose collar on the crank-shaft having on its outer end a toothed wheel and journaled loosely on the same one end of a tubular hub provided with a toothed wheel of the 105 same size as the toothed wheel on the collar, the inner end of the collar being connected with a train of multiplying gearing which acts on the opposite end of the hub, and the outer end of the collar brought into unison with 110 the hub by means of a wide-faced gearing attached to the boxing, substantially as herein set forth.

Signed at New York, in the county of New York and State of New York, this 12th day of August, A. D. 1890.

GEORGE H. CHAPPELL.
